METHOD AND MEANS FOR CONVERTING
OIL-BURNING FURNACES TO COAL-
BURNING ONES

Morris H. Garfunkle, Newark, N. J.

Application October 17, 1942, Serial No. 462,326

3 Claims. (Cl. 126—176)

This invention relates to means for converting oil-burning furnaces or boilers to coal-burning ones.

In the past few years many coal-burning furnaces or boilers have been "revamped" for the purpose of using oil. Now with the shortage of oil a large number of these furnaces or boilers must be reconverted to use coal. In many cases this presents a considerable problem for the reason that I have found, in making contacts with these installations, that in 80% to 90% of the first conversion the ash-pit door frame of the furnace or boiler was removed and the ash pit reconstructed to accommodate at least parts of the oil burner mechanism, and other changes made so that standard grate bars, if not thrown away or junked, cannot be used in the reconversion.

To meet these and other difficulties, I have worked out an arrangement which will allow re-conversion of furnaces or boilers of different makes and sizes from oil-burning back to coal-burning at a minimum cost of material and labor. My plan or process of re-conversion of oil-burning furnaces or boilers to burning coal is exemplified in the annexed drawings wherein:

Figure 1 is a view on a reduced scale of the front of a boiler showing the same after conversion to burning coal has been made.

Figure 2 is a view on an enlarged scale on the line 2—2 of Figure 1.

Figure 3 is a plan view of the installation on the line 3—3 of Figure 2.

Figure 4 is a view on the line 4—4 of Figure 3.

Figure 5 is a view on the line 5—5 of Figure 3.

Figure 6 is a fragmentary view showing one of the conversion steps as applied to a grate bar.

Figure 7 is a fragmentary view of one end of a grate bar showing a further step in the conversion process.

Figure 8 is a fragmentary view of one end of a grate bar rest, illustrating part of one of the conversion steps.

Figure 9 shows a modified form of grate rest support.

Figure 10 shows a further modified form of supporting the grate rests.

In the drawings wherein like numbers refer to corresponding parts, 1 illustrates generally a furnace which has been converted from oil to burning coal. In making this conversion it is to be understood of course that the oil burner is removed from the furnace. Fire bricks 2 are first installed on two sides and the rear of the ash pit as shown in Figure 3. I have found it good practice to have the height of this fire brick

wall approximately one inch below the low-water leg or portion of the furnace or boiler. After the fire wall has been built, a pair of grate-bar supports or rests 3 and 4 are positioned at the rear and front portion of the ash pit as shown in Figure 3. Each grate rest is provided with a plurality of lugs 5 forming rests 6 for receiving the bearing ends 7 and 8 of the grate bars. The forward portion 8 of each grate bar is preferably circular and at each end of this portion 8 there are provided annular collars 9 and 10 to properly locate the grate bar over the ash pit.

In Figure 3 I have shown six grate bars which are of standard size, each having twenty-two wings or teeth 11 extending laterally from each side of the central bar portion 12. Each grate is $3\frac{1}{16}$ " in width, and the space between the oppositely disposed teeth is $\frac{1}{16}$ " so that the grates are disposed on 4" centers. This gives a total grate width of 24". This is much too wide for the average furnace or boiler which will only take four to five grates. In the event that only four grate bars are needed, the grate rests may be shortened by drilling a hole 13, as illustrated in Figure 8, and breaking off the portion 14, it being understood that the grate bars and grate bar rests are made of cast iron.

After the hole 13 has been drilled, as indicated, the end portion 14 may be readily broken off. If necessary, the small part 15 left on the portion 16, which now becomes an end support for the grate rest, may be ground off with a portable electric grinder. If the grate bars themselves are too long, they may be readily shortened as indicated in Figures 6 and 7. This is done by drilling a hole 17 through the main bar 12 at the necessary distance from the rear end of the grate bar. Then to provide a rest portion 1 for engaging the seat 6 in the grate rest, two teeth 18, shown in dotted lines in Figure 7, may be readily broken off the central rib or body portion 12 of the grate bar, thereby giving a support end corresponding to 1 in Figure 6, it being understood that the longitudinal spacing of the teeth 18 along the bar 12 is such that when two oppositely disposed pairs, shown by the dotted line 18, are broken off, the necessary support portion 1 is obtained.

It is to be noted that the bars 12, forming the backbone of the grate bars, have a cross-section 50 similar to that shown in Figures 6 and 7 so that the forward projecting ends 19, which extend beyond the front of the furnace, are each adapted to receive a shaker bar. If these extending portions 19 are found to be too long, they may be 55 cut off as indicated by the dotted line 20 in the

same manner as illustrated and described with respect to Figure 6.

In some furnaces or boilers it may be found necessary to install a front plate 21 as indicated in Figure 1. This plate has clearance holes 22 for the ends 19 of the grate bars, and this clearance is sufficient so as to allow the ends of the grate bars to be lifted up a distance in the recesses 6 so as to release a piece of coal or coke which may be wedged between the grate teeth. Furthermore, the inner annular flange 10 of each grate bar coacts with a flanged portion 23 on the forward grate rest to give a shearing action against any piece of coal or coke that may tend to become wedged at this point. Due to the flanged portions 23 on the grate rest 4, spaces or recesses are provided between the flanges 23 which protrude into close juxtaposition to the collars 10, thereby allowing a space for the portions of the coal or coke that are sheared off by the rotating action of the collars 10 to pass these broken-up pieces down into the ash box, instead of becoming wedged in the narrow space between the inner edge of the grate rest 4 and the outer teeth 11 of the grate bars if these recesses were not provided.

After the grate bars have been installed as heretofore described, the front end of the ash pit is closed up with fire brick 24 and at the same time an ash door 25, carrying a draft shutter 26, is installed by suitable hinged supports attached to the masonry or fire brick 24. The shutter 26 is held in any adjusted position by a pawl 32 which is adapted to engage notches 33 cast in the door 25. The shutter 26 may be operated by any suitable means attached to a lug 34 on the shutter.

Instead of supporting the grate rests 3 and 4 on the top of the side brick wall as shown in Figure 3, they may be supported on short pipe sections 27, each of which has a bottom support flange 28 and a support plate 29 to which the end of the grate rest 3 or 4 is fastened as by a bolt 30 as shown in Figure 9; or the ends of the grate rests may be fastened to an angle bracket 31 attached to the side of the furnace 1 as shown in Figure 10. Furthermore, while reference has been made to the use of plate 21, the masonry 24 may be built up around the shaker ends 19 of the grate bars, leaving, of course, clearance holes 22, and where in the claims I have referred to an ash-pit door, this means both the frame and the door and directly associated parts.

From the foregoing it is to be understood that certain of the minor details and steps may be varied without departing from the substance of my improved construction and conversion process. It will also be understood that in changing the length of the grate bars and their supports as described, the parts that are broken off are not wasted as they are returned to the foundry and recast with other parts.

I have found, from actual contact with other means now being offered on the market, that the parts and methods of procedure set forth in the foregoing description are not only a very cheap and economical arrangement, but a highly satisfactory conversion means for transforming present oil-burning furnaces or boilers to coal burners.

What I claim is:

1. The process of conversion as herein set forth which consists in rebuilding a new ash-pit chamber, placing support means within the ash-pit

chamber for grate rests, providing grate rests which may be longer than the length required for the particular furnace, said grate rests having lugs to receive grate bar ends, removing some of the metal at a selected place adjacent the ends of the grate rests for shortening the grate rests, if necessary, to give the desired lengths of the rests, and then breaking off these end sections at the places where the metal has been removed, then placing one of these rests on the front support parts and another on the rear support parts, providing grate bars each having a central rib or body portion with wings or teeth laterally from each side of said central portion, removing some of the metal from the central rib at a selected place adjacent the ends of the bars for shortening the grate bars, if necessary, to give the desired length of bars, and then breaking off these end sections at the places where the metal has been removed, also breaking off teeth from the grate bars if necessary and then placing these toothed grate bars across said rests in said lugs for rotation thereon and installing a new ash-pit door where the oil burner entered the old combustion chamber, and a front closure plate having clearance holes for fitting over the shaker ends of the grate bars.

2. Means for converting oil-burning furnaces or boilers, having a space adapted for an ash pit and into which an oil burner extended, to coal burners, said means including an ash pit composed of fire bricks on at least two side and one rear wall of the adaptable ash-pit space, grate rests mounted on said side bricks at the front and rear and across the top area of the adaptable ash-pit space and having lugs thereon and toothed grate bars rotatably mounted on said rest lugs, each grate bar having a pair of spaced annular collars at the shaker end for positively positioning the bars in the front grate rest, while the grate rests have formations producing recesses extending between adjacent grate bars and adjacent the end teeth of the grate bars to act cooperatively therewith and get a shearing action for the purpose described, said grate bars having a central rib or body portion with teeth or wings disposed thereon, the said rests and bars being normally of a length to fit the largest household furnace or boiler, the grate rests and grate bars having a plurality of spaced weakened places, whereby certain of the lugs on the grate rests and teeth on the grate bars with parts of the central rib or body portion may be removed when necessary in the manner specified herein to readily accommodate the rests and bars to furnaces or boilers of different sizes.

3. Means for converting oil-burning furnaces or boilers, having a space adapted for an ash pit and into which an oil burner extended, to coal burners, said means including an ash pit composed of fire bricks on at least two side and one rear wall of the adaptable ash-pit space, grate rests mounted on said side bricks at the front and rear and across the top area of the adaptable ash-pit space and having lugs thereon and toothed grate bars rotatably mounted on said rest lugs, each grate bar having a pair of spaced annular collars at the shaker end for positively positioning the bars in the front grate rest, while the grate rests have formations producing recesses extending between adjacent grate bars and adjacent the end teeth of the grate bars to act cooperatively therewith and get a shearing action for the purpose described, the grate bars at

their shaker ends being liftable to an extent from their lug seats to further assist in clearing the bars of clinkers or the like, said grate bars having a central rib or body portion with teeth or wings disposed thereon, the said rests and bars being normally of a length to fit the largest household furnace or boiler, the grate rests and grate bars having a plurality of spaced weak-

ened places, whereby certain of the lugs on the grate rests and teeth on the grate bars with parts of the central rib or body portion may be removed when necessary in the manner specified herein to readily accommodate the rests and bars to furnaces or boilers of different sizes.

MORRIS H. GARFUNKLE.
